UNITED STATES PATENT OFFICE.

CHARLES A. CULVER, OF NORTHFIELD, MINNESOTA, ASSIGNOR TO WIRED RADIO, INC., OF NEW YORK, N. Y., A CORPORATION OF DELAWARE.

MICROPHONE.

Application filed May 10, 1926. Serial No. 108,103.

My invention relates to an improved type of microphone which is designed particularly for use in connection with radio-broadcasting and public address systems.

5 One of the objects of my invention is to provide a microphone or pick-up device in which the customary vibratile diaphragm does not form an essential part or element in its construction and operation.

10 Another object of my invention is to provide means whereby the so-called "carbon hiss" is materially reduced.

15 A further object of my invention is to prevent "packing" of the granular material commonly used as an element in microphonic devices.

The invention will be understood by reference to the accompanying drawings in which:

20 Figure 1 illustrates a cross-sectional view through a microphone embodying the principles of my invention; Fig. 2 is a cross-sectional view through a modified form of microphone construction in accordance with the 25 principles of my invention; and Fig. 3 shows a still further modification of the microphone construction of my invention.

Figure 1 shows in cross section a preferred form of the invention. The body of the 30 microphone designated as 1 in the drawing, consists of a solid block of marble, glass, porcelain or other relatively heavy insulating material which forms a non-vibratile form and support for the several elements 35 constituting the device. Two rectangular carbon "mirrors", or other suitable electrodes 3 are securely attached to the body in recesses provided for that purpose in the cut out portion 2 in the block. Terminals 4 are 40 attached to the electrodes 3 whereby the microphone may be connected in series with the usual source of potential and primary of a transformer. Granular microphonic material 5 occupies the V-shaped space between 45 the electrodes 3. Above the granular material, and also in the interstices between the particles of granular material, is placed a non-conducting liquid 6, such as chemically pure water, alcohol, or other similar liquid.

50 The granular material 5 thus is immersed in said liquid 6 and is also covered by it. A thin layer of oil 7 prevents the evaporation of the water, alcohol, or other liquid 6 beneath.

55 Heretofore a vibratile diaphragm has been

utilized for the purpose of transferring the energy of the incident sound waves to the electrodes or granular material, or the sound waves have been caused to impinge directly upon the granular substance. In those devices of the former type it has been found necessary to subject the diaphragm to relatively high peripheral tension in order that the natural period of vibration of the diaphragm be above the highest frequency employed in music. This arrangement results in comparatively low sensitivity as well as a non-linear response to sound disturbances of varying intensity.

60 My invention dispenses with the usual diaphragm with its attendant disadvantages and substitutes therefor a means whereby a relatively great amount of energy of the incident sound waves is transferred to all of the granular particles. This is accomplished 65 by means of the liquid 6 which forms a part of the device. As a result of the operation of Pascal's principle the pressure due to the incident sound waves is transferred without loss to all of the granular material 5. Thus 70 the total effect of a sound wave is materially greater than would be the case if the liquid 75 were not present. Experiment shows that the sound sensitivity of a microphone having a liquid 6 as one of its elements is several fold greater than one without that feature.

80 Further, in any pick-up device employing such granular material as carbon the minute electric arcs formed between the particles 85 of microphonic material give rise to what is known as the "carbon hiss" which, when amplified, produces a very undesirable background of extraneous sound. The presence 90 of the non-conducting liquid in my invention inhibits the formation of these minute arcs, thus materially reducing the "carbon hiss". The presence of the liquid also acts to prevent the "packing" of the granular material 95 with attendant loss of sensitivity.

100 Figure 2 shows one of the practical forms of my invention. In this arrangement 8 designates a lower block member which is bridged across the top thereof by an upper block member 9. The block members 8 and 9 are suitably united by means of screws 10. The recess 11 which is provided in the upper block portion 9 registers with a recess 12 in the lower block member which serves 105 as a pocket or seat for a carbon ring mem- 110

ber 13 which surrounds a central carbon button or electrode 14. The ring member 13 and central carbon button 14 serve as opposite sides of the microphone and leads 15 and 16 extend therefrom. The granular conductive material 17 occupies the space between the carbon ring member 13 and the central electrode 14. This material is covered by the liquid 18 such as alcohol, which 10 is in turn covered with a film of oil 19.

Figure 3 shows a form of construction of my invention in which a deflecting surface 30 is utilized for the purpose of reflecting horizontally moving sound waves onto 15 the liquid surface of the microphone proper. Such a type may be used in connection with the transmission of speech and certain types of music.

In this figure I have shown a block 20 20 having a recess 21 therein in the lower portion of which I mount at spaced intervals the carbon blocks 22 and 23 which connect through leads 24 and 25 to the control circuit. The space between the carbon mirrors 25 22 and 23 is filled with the granular material 26 which is in turn covered by the liquid 27 having a film of oil 28 thereover. The deflecting surface 30 is secured adjacent one side of the block 20 by any suitable means, 30 such as screws 29. This arrangement permits the placing of the microphone on a vertical stand convenient to the broadcast artist or in a position where music may be readily directed against the sensitive elements 35 of the microphone.

I have found the construction of this invention highly sensitive in its operation, and while I have shown the invention in a number 40 of its preferred embodiments, I desire that it be understood that modifications may be made and that no limitations upon the invention are intended other than are imposed by the scope of the appended claims.

What I claim as new and desire to secure 45 by Letters Patent of the United States is as follows:

1. A device for converting sound vibrations into variable electrical current which comprises an insulated block member, a pair 50 of conductive electrodes mounted in said block member and substantially covered by conductive granular material, a pool of liquid covering said granular material and a film of oil on the surface of said liquid for providing a sound transmitting medium for effecting variations in pressure through said 55 granular material for varying the conductivity between said electrodes in accordance with sound vibrations.

2. A device for converting sound vibrations into variations of electrical current, the combination of an insulated body structure recessed to receive a pair of electrodes therein, a mass of granular particles substantially 60 covering said electrodes and a pool of liquid

over said granular particles for transmitting pressure effects derived from sound waves incident upon the surface of said liquid for varying the conductivity across said electrodes in accordance with variations in 70 sound.

3. A device for converting sound vibrations into variable electrical currents comprising an insulated body structure recessed to receive a pair of electrodes, a body of 75 granular material arranged to substantially cover said electrodes, a pool of fluid in which said granular material is substantially immersed, and means for directing sound waves against the surface of said pool of 80 liquid for imparting variable pressure to said granular body for changing the electrical conductivity between said electrodes in accordance with sound vibrations.

4. A device for converting sound vibrations into variable electrical current, comprising a horizontally extending insulated body structure recessed to receive a pair of electrodes, a body of granular material arranged to substantially cover said electrodes, 90 a fluid body in which said material is arranged to be immersed, a sound deflecting surface secured to said body structure for directing sound waves incident thereon against said fluid body for creating variations in 95 pressure through said granular material in accordance with variations in sound vibrations.

5. A device for converting sound vibrations into variable electrical current, comprising in combination an insulated body structure recessed to receive a pair of electrodes spaced apart and disposed at an angle with respect to each other, a body of granular material arranged between said electrodes, a fluid body substantially covering 100 said body of granular material for receiving sound vibrations directed thereagainst and transmitting pressure effects to said body of granular material for changing the electrical 105 conductivity between said electrodes in accordance with variations in the amplitude of sound vibrations.

6. A device for converting sound vibrations into variable electrical current, the 110 combination of an insulated body structure having a substantially conical recess therein, a pair of electrodes spaced one from the other and arranged substantially in the form of a V, a body of granular material arranged to substantially fill the space between said electrodes, a pool of fluid substantially covering said body of granular material and arranged to receive sound vibrations and transmit the pressure effects thereof to said body 115 of granular material for changing the electrical conductivity between said electrodes in accordance with sound vibrations.

In testimony whereof I affix my signature.
CHARLES A. CULVER.
